UNITED STATES PATENT OFFICE.

GEORGE E. WEBB, OF MILWAUKEE, WISCONSIN, ASSIGNOR TO KOEHRING COMPANY, OF MILWAUKEE, WISCONSIN, A CORPORATION.

DISCHARGE MECHANISM FOR CONCRETE MIXERS.

Application filed March 27, 1926. Serial No. 97,962.

The present invention appertains to concrete mixing machines and especially takes into consideration the large types of such machines which are at present being put into common use, the invention involving primarily a special novel design of discharge means for such mixing machines. Where concrete mixers are of large capacity the aggregates handled thereby are very heavy and it is at present common to employ considerable power for the operation of the discharge chute ordinarily used for emptying the mixing drum. Such power is needed because the weight of the gravitating aggregates in the drum is so great that in large type mixers manual power cannot be used for manipulating the discharge chute to render it operative for its purposes. The foregoing is exceptionally true when the discharge chute is a part of the mixing function of the machine and acts as a mixing element upon which the gravitating aggregates drop and are returned to the receiving end of the mixer.

The present invention has been evolved with a view primarily to utilizing the gravitational forces set up by the raising and dropping of the aggregates while mixing to assist by impact action upon the discharge chute, the actual operation of said chute. To this end, I use a special construction of chute designed to avail of the impact action of the aggregates during their descent while being agitated, whereby the power necessary to actuate the chute mechanism is relatively small.

This invention also involves certain control and operating mechanism for applying positive power for operation of the discharge chute where the latter is of revolving type, whether or not the action of the chute is assisted by the impact of the concrete aggregates in the process of mixing them in the mixing drum.

Supplemental to the foregoing, the present invention furthermore, includes certain novel mechanism for effecting the movements of the discharge chute for placing the same in a discharging or non-discharging position, under control of a batchmeter as customarily used in conjunction with a concrete mixing machine.

The invention in another phase thereof, may be said to comprise novel means whereby a discharge chute of the revolving, or even a different type, may be operatively connected with the mixing drum and the power of rotation of the latter transmitted to the discharge means for causing it to assume proper operative positions to perform its various functions.

In the accompanying drawings, there are shown typical constructions illustrating certain adaptations of the invention, for the purposes above outlined. In these drawings the figures may be briefly described as follows:

Figure 1 is a front elevational view of a concrete mixing machine embodying the invention, and the same may be of a stationary or portable type.

Figure 2 is a side view of the machine, a portion of the mixing drum broken away to show more clearly the arrangement of the discharge chute.

Figure 3 is a side elevational view of the discharge chute alone.

Figure 4 is a cross-sectional view through the body of the discharge chute showing more clearly the formation of the impact members or wings carried thereby.

Figure 5 is a diagrammatic view illustrating more clearly how the falling concrete aggregates are caused to act with their impact forces upon the chute during the revolution of the drum so as to tend to operate the chute in a revolving manner.

Figure 6 is an enlarged view showing more clearly the mounting of the discharge chute upon the frame, certain parts being illustrated in section to bring out detail features of construction.

Figure 7 is a fragmentary sectional view illustrating more clearly the supporting rollers engaging the annular race surrounding the chute and assisting to support the latter in its rotary turning movement.

Figure 8 is a detail sectional view bringing out more clearly the engaging dog and trip lever parts of the control mechanism by which the power is caused to be applied to the chute for turning the same from the drum.

Figure 9 is a side view showing particularly the parts illustrated in Figure 8.

Figure 10 is a view partially illustrating the chute flange in elevation, and showing 5 in section the control mechanism previously referred to.

Figure 11 is an end view of the control mechanism parts.

Figure 12 is a view largely in section of 10 the restoring slide of the control mechanism.

Figure 13 is a side view of the actuating slide of the control mechanism.

Figure 14 is an edge view showing the actuating and restoring slides assembled in 15 their cooperative position.

Referring to Figures 1 and 2, it will be noted that I provide a base frame 1 and a vertical frame 2 upon and in which the mixing drum 3 of my mixing machine is 20 mounted. Said drum is supported upon rollers 4 as usual and is equipped with ring gears 5 engaged by spur gears 6 that rotate under power transmitted from a suitable engine and thereby drive the drum in the 25 known manner. My discharge chute mounting is best shown in Figures 1, 2, 6 and 7, from which it will be observed that the chute is designated 7 and is adapted to revolve by reason of the provision of supporting means shortly to be set forth. The chute 7 comprises important construction including a body equipped at its sides with oppositely extending impact wings or sides 8, and also oppositely extending flanges 9, 30 35 one flange extending opposite to each wing and forming with the wing at the same side of the chute body a sort of trough-like chute formation.

The angularity of the formation of the impact sides or wings 8 projecting from the body of the chute 7 is such that as the drum 3 revolves and carries upwardly by its mixing buckets and mixes the contents thereof, comprising concrete aggregates, the said aggregates as they gravitate from the elevating buckets and blades are caused to strike against the inner face of the wing or side 8 which is uppermost according to the adjustment of the chute. The wing or side 50 55 8 of the chute may be said to be eccentric respecting the axis of the drum and on this account the impacting forces received by the particular wing or side 8 which is uppermost have a tendency to impart rotary movement to the chute 7. Of course, such movement may be resisted by maintaining the chute locked. However, on account of the peculiar action of these impacting forces, it will be evident that they may be availed of as a source of power to be applied to the chute for turning it, when the turning movement is desired or required for enabling the chute to assume a discharge position, or causing it to assume a non-discharging position

wherein it may constitute a mixing element. The body of the chute 7 inclines at a considerable angle to the axis of the drum so that obviously when the chute is in the position of Figure 2 the aggregates falling thereon will be caused to be fed back toward the receiving end of the drum, whereby the chute performs a re-mixing function. Or, when the chute is turned sufficiently to reverse the inclination of the same, as seen in Figure 2, or assume the inclination in which it is illustrated in Figure 6, the aggregates which drop upon the chute will be caused to discharge out of the discharge opening of the drum 3 in which opening the chute is mounted.

The chute 7 includes a body construction also comprising a disc-like member in the form of a circular flange 10 extending radially from and surrounding the outer end portion of said body. Additionally, the chute 7 is equipped with an outstanding flange 11, a portion of which is outwardly and upwardly inclined as shown at 11^a to provide a race way against which bearing anti-friction and supporting rollers 12 engage and operate. Two of the rollers 12 are preferably used and they are arranged beneath the flange 11 at spaced points below the horizontal axis of rotation of the chute. The rollers 12 are carried by journal members 13 which have bearings in suitable brackets 14 attached to the framework 2 of the machine.

The said horizontal axis of the chute 7 comprises a pivot member 15 seen best in Figure 6 as engaged with a projection 7^a on the body of the chute, said pivot member being journaled in a rockable bearing bracket 16 having a rocking pivot connection at 17 with pivot lugs 18 that project upwardly from a base plate 19 carried by a cross channel 20 secured in a substantial manner to the framework 2. The arrangement of the bearing rollers 12 and the axial pivot member 15 which support the chute for rotation permits of a slight rocking or floating movement of the chute upon the rocker bearing pin 17 as an axis.

The formation of the annular flange 10 or disc-like projection 10 of the chute is such that this member, together with the body proper of the chute forms a closure for the discharge end of the mixing drum 3 which closure is operated when the chute 7 is in non-discharging position, that is, inclined downwardly and inwardly in the drum 3. When the chute 7 is revolved so that its body assumes the opposite inclination as shown in Figure 6, the said chute provides an effective discharging area or opening through which the contents of the mixer may pass to the outer stationary discharge chute 21. The flange 11 is provided

with an outwardly projecting lip or extension 22 which has a close fit connection with the outer stationary discharge chute 21 into which the contents of the drum 3 will pass 5 in the process of discharging the same therefrom through the means of the chute 7.

The chute 7 is provided at the flange 10 with an inwardly projecting flange portion 23 which actually enters the drum discharge 10 opening as seen in Figure 6. At the inner extremity of this flange 23, there may be secured in an annular groove surrounding the chute, a flexible ring or washer-like member 24 for closing the space between the chute 15 and the drum discharge opening. This member 24 may be made of rubber or some such material if desired, though I do not wish to be restricted to a resilient substance within the purview of this invention. 20 The member is attached to the chute by suitable fastenings 25.

Referring now to Figures 10 to 14 inclusive, in conjunction with Figures 8 and 9, I shall describe the control mechanism used 25 by me for connecting the drum 3 intermittently, and either manually or automatically as desired, with the chute 7, in order to apply mechanical power thereto to supplement the power of the impact forces that may operate 30 upon the wings 8 of the chute. Or, should my chute 7 be constructed without such wings 8 the power feature now to be set forth will do the necessary in operating and restoring the chute so that it may perform 35 its several functions.

Figure 1 shows mounted on the frame 2, a batchmeter A of known construction such as disclosed for instance in Winkler Letters Patent #1,451,483 issued April 10th, 1923. 40 This batchmeter is ordinarily controlled in its action by the loading skip used to raise and charge concrete aggregates into the receiving end of the drum 3. The batchmeter operates to predetermine the amount of time 45 required for properly mixing the aggregates in the drum 3 and involves actuating means to at such time permit the discharge of the contents of the drum. It suffices to state that said actuating means involves a shaft 50 27 having an arm 28, see Figure 1, the arm 28 connected by a rod 29 with an actuating slide 30, see Figures 10 to 14 inclusive. The actuating slide 30 operates between the side flanges 31 of a restoring and control slide 32. 55 The slides 30 and 32 are mounted for vertical movement in a casing 33 provided for the control mechanism now described. At its lower portion, the actuating slide 30 has a kick-off dog 34 pressed outwards by the 60 spring 35. The dog 34 is arranged to coat with a roller carried by the lower end of a locking lever 36 pivoted at 37 in the casing 33 and normally actuated by a spring 38 to move the lower end thereof with the roller 65 aforesaid into engagement with said dog

34. The upper end of the lever 36 has a nose which normally engages a locking cam 39 on slide 30, the function of which will appear fully hereinafter. On its outer side, the lever 36 is formed with a locking lug 40 70 engageable by the locking arm 41 of a locking lever or arm 42. The locking arm 42 is mounted on and fixed to a shaft 43 equipped with an upper fixed arm 44 and a lower fixed arm 45. A rod 46 is connected with the 75 upper arm 44, and a handle 47 is connected with the lower arm 45.

The primary function of the locking lever 36 is to engage an abutment 48 on the lower portion of the restoring and control slide 80 32 and the purpose of the dog 34 is to kick the lower end of the lever 36 out of engagement with the abutment 48 aforesaid. At its inner side, the control slide 32 has a cam 32^a adapted to ride in contact with a roller on the outer end of a push lever 49 pivotally mounted at 50 on the upper end of a rockable supporting lever 51 which is pivoted at 52 and equipped with a stop arm 53. A spring 54 is connected with the push 90 lever 49 and normally tends to pull the same with the lever 51 outwardly to maintain the roller of lever 49 in contact with the cam 32^a. The push lever 49 at its intermediate portion is equipped with a stop or 95 limiting arm 55 which controls the extent of rocking movement of said lever upon its supporting lever 51. Above the lever 49 is located a spring 56, one end of which engages 100 a pin 57 on the control slide 32 and tends to project said slide upwardly whenever it is released from the action of the locking lever 36.

The push lever 49 is arranged to engage and move pivotally a catch or pawl member 58 which is formed with an integral trunnion 59, see Figure 8, which trunnion is mounted in a suitable bearing 60 on the flange 10 of the chute 7. The trunnion 59 passes through the bearing 60 and has on its outer end a squared portion 61 that carries a trip lever 62, the parts 58, 59 and 62 being suitably assembled by the application of a nut 63 to the threaded end of the trunnion 59. The lever 62 has a square opening fitting 110 on the square portion 61 of the trunnion so that the parts 58 and 62 rock together. On the trip lever 62 is a pin 64 operating in a slot 65' in the flange 10, affording a pin and slot movement pivoting arrangement 115 for the parts 58 and 62.

The catch member 58 is adapted, when pushed toward the extended axis of movement of drum 3 by the push lever 49, to engage with any one of a series of actuating lugs 65 that project outwardly from the head of the drum 3 in which is formed the discharge opening at which the chute 7 is arranged. Obviously if the catch 58 is engaged with anyone of the said lugs 65 pow- 120 125 130

er is applied to turn the chute 7 from the drum 3 itself, and the catch 58 with flange 10 and chute 7 will rotate with drum 3 so long as said catch 58 remains in engagement with a lug 65.

Mounted above the casing 33 and on a bracket carried thereby, is a restoring lever 66 one end of which is arranged in the path of travel of rollers 67 carried by the 10 flange 10 of the chute 7. As a convenient method of mounting the rollers 67, I avail of the bearing members 60 in which the trunnions 59, see Figure 8, are mounted. The rollers 67 are journaled to turn about the parts 60 as journals therefor.

Carried by the vertical member of the frame or frame work 2 is a stationary abutment pin 68 off-standing from a suitable bracket 69 and disposed in the circular path 20 of movement of the tail ends of the trip lever 62 that is to say when the said levers 62 assume the positions of the dotted lines of Figure 9, their tails move in a path intersecting the pin 68 and will be struck by 25 the latter and forced inwardly to disengage the catch member 58 from the lugs 65 with which it happens to be engaged, thereby freeing the chute from the driving connection established with the drum 3.

30 In operation, it will be assumed that the drum 3 is rotating in its normal condition of operation. While the drum is mixing the aggregates, the chute 7 is in the position of Figure 2. The batchmeter A has been 35 previously set by the loading skip or otherwise for a control of the mixing operation. At the end of the proper mixing period, the batchmeter A operates and raises the rod 29. The actuating slide 30 is thus elevated 40 causing its dog 34 to kick the lower end of the locking lever 36 from the abutment 48 of the control slide 32. The control slide 32 is immediately impelled upward by means of the spring 56. This results in the pushing 45 out of the push lever 49 by the cam 32^a, thereby moving the catch member 58 into the path of rotation of the adjacent lug 65 of the series of lugs on the drum 3. As the catch member 58 is carried by the chute 50 flange 10, as soon as it engages the lug 65 of the drum, the chute will be turned by the drum 3. The rotation of the chute will continue until it has been reversed, practically speaking, from the position of Figure 2 to its position of opposite inclination shown in Figure 6, a turning of about 180 degrees. When said chute has made the stated one-half revolution, the tail of the trip lever 62 will strike the abutment pin 68 on the frame 60 2 and the catch member 58 will thus be tripped out from its engagement with the lug 65 and the driving action of the drum 3 on the chute cut off or discontinued. There are two of the catch members 58 employed with their trip levers 62 and they

are arranged at diametrically opposite points on the flange 10 in respect to the axis of the chute. Therefore when the catch member 58 which has caused the turning of the chute is tripped to release the chute from the drum 3, the opposite catch member 58 will approximately at this moment of release strike a stop arm 70 mounted on the frame 2 somewhat opposite the abutment pin 68. A positive stopping of the rotation of the chute will thus be effected just as the same is released from the drum. The inter-engagement of the parts 58 and 70 is best shown in Figure 10, the catch member 58 having a shoulder portion 58^a that abuts with the stop arm 70. This shoulder portion is disengaged from the member 70 whenever the push lever 49 acts in the manner previously stated.

25 The chute 7 is then disposed in its discharge position and locked there, free to remain stationary because of release from the drum. The contents of the drum 3 are then discharged by the chute 7 and the next requirement is to operate provided means for 30 restoring the chute 7 to its nondischarging position at which, in the present instance, it performs a mixing function.

35 Previous to describing the restoration action of the chute, it is notable that after the control slide 32 performed its function of inter-engaging the parts 58 and 65, one of the rollers 67 will shortly thereafter strike the restoring lever 66 and force the control slide 32 downward until it is re-engaged by the locking lever 36 and held in the downward position at which time the push lever 49 has been pulled back by the spring 54 out of the path of movement of the catch member 58 as it comes around with the flange 10. 40 The actuating slide 30 will remain up however, until the batchmeter is reset by the loading skip on the next raising movement of the skip subsequent to that which performed the batchmeter setting function previously referred to. With the parts so arranged, the operator of the machine can readily restore the chute by pulling outwards on the handle 47, such action again 45 rocking the locking lever 36 out of engagement with the abutment 48 of the control slide 32, the said slide 32 again being impelled upwardly under the action of the spring 56 and the push lever 49 going through the operation previously set forth 50 to again connect the chute flange 10 with the drum 3 and turn the chute another half revolution until it comes to a stop under the influence of the parts 58 and 70. The chute 55 will at this time have resumed its original or nondischarging position. The reason the operator may move the handle 47 as stated is because the slide 30 is raised and held raised as previously mentioned, thereby elevating 60 its cam abutment 39 placing the latter out 65

of engagement with the upper end or nose of the locking lever 36 and permitting said lever 36 to be rocked by the impingement of the arm 42 therewith at its outer side. When 5 the batchmeter is reset and the actuating slide 30 is restored so that the chute is again placed under the control of the batchmeter, the abutment 39 will engage the lever 36 and prevent the operator from interfering 10 with said control by moving the handle 47. Under these conditions, therefore, it is impossible for the operator to cause a rotation of the chute 7 before the batchmeter is connected up with the member 30 by a 15 rod 29.

It will be obvious, however, that should it be desired to dispense with the batchmeter A entirely, this may be done by omitting the parts A, 27, 28, 29 and 30, and the control involved thereby, and depend solely on 20 the manual releasing of the control slide 32 by the rocking of the locking lever 36 through movement of the handle 37.

If the batchmeter control mechanism just 25 above referred to is dispensed with, I may utilize the rod 36 and arm 44 as a means to be actuated by the loading skip of the mixer to release the control slide 32 and thereby connect the discharge chute with the mixer 30 to turn the chute to a non-discharging position as a fresh batch of aggregates is charged into the mixer. Thereafter, a manual control action of the handle 47 may cause the 35 discharge of the aggregates from the mixer in the manner previously stated. This general method of restoration to a non-discharging position of the discharge chute is exemplified by Robb Letters Patent #1,370,497, issued March 1, 1921.

40 Reference is made to Figures 7 and 8 which show that the trunnion member 59 carries a resilient washer member 75 which when the nut 63 and other adjacent parts are assembled, is tensioned to draw the friction ring 76 into engagement with the concavity in the outer end of the bearing part 60, and with the enlargement 58' on the catch member 58. In this way, friction between the parts prevents any loose movement 45 of the members 62 and 58, and holds these parts in the positions to which they are moved by their cooperating members.

50 While my mechanism has been described with special reference to a rotary type of construction of chute, it will be recognized that the invention is not limited in its application and advantages to such type of chute alone.

55 Again referring to the rotary chute or discharge device construction, I draw attention to the fact that effectively speaking, my discharge device consists of the chute 7 having the discharge portion 7^x and the mixing portion 7^y. The discharge device, of course, 60 projects into the mixing zone of the mixing

drum 3 so that its impact members may be actuated by the agitated aggregates in the mixing drum as previously set forth. But the discharging portion 7^x and the mixing portion 7^y are separate and distinct parts of 70 the discharging device, and they are operative independently of each other though of course carried by the same support.

Another phase of the invention resides in the peculiar control of the operation of the 75 discharge device 7. There are occasions in the use of a concrete mixer when it is not desired to render discharge means operative upon the lapse of the mixing period controlled by the batchmeter A. This delay 80 of action of the discharge is not harmful because the required time of mixing the aggregates has passed. It would be harmful, however, if it were possible for the operator to actuate the discharge chute or 85 means before the lapse of the mixing period, but this kind of operation is expressly provided against by my invention. Suppose it be desired to delay the operation 90 of the discharge device beyond the mixing period controlled by the batchmeter A. In such event, the handle 47 is pushed inwardly to lock the lever 36 against movement through cooperation of the arm 41 therewith. When this is done, it will be 95 apparent that when the batchmeter A operates, the actuating slide 30 is prevented from rising at the end of the mixing period. Such action of preventing the upward movement of slide 30 is compensation by certain 100 spring or resilient parts (not shown), in the batchmeter, and with which parts the slide 30 and its rod 29 are connected. When the time has arrived to permit the delayed 105 setting of the discharge portion 7^x in operative position, the handle 47 may be pulled outward to release the part 30 from the locking arm 41 and the slide 30 will then move upwards quickly, actuate the kick-off dog 34, and thus release the slide 32 from 110 the lever 36. The slide 32 then immediately causes coupling of the chute 7 with the drum 3 and the turning of the chute to its discharging position.

115 Matters of invention disclosed herein but not claimed, are claimed in my co-pending applications, one covering "improvements in rotary discharge chutes" for concrete mixers, filed March 27, 1926, Serial No. 97,963, and the other covering "improvements in 120 concrete mixing machines," filed September 25th, 1926, Serial No. 137,665.

Having thus described my invention, what I claim as new and desire to secure by Letters Patent of the United States, is:—

125 1. In a mixing machine, the combination of a mixing drum, a rotatable discharge chute therefor mounted to move angularly coaxially with the axis of rotation of the drum, and means for operatively connecting 130

- the drum with the discharge chute for rotating the chute with the drum.
2. In a mixing machine, the combination of a mixing drum, means for rotating said drum, a rotatable discharge chute for the drum mounted to move angularly coaxially with the axis of rotation of the drum, and means for establishing intermittent connection between the chute and the drum for transmitting the movement of the drum to the chute.
3. In a mixing machine, the combination of a rotating mixing drum provided with a discharge opening, a rotatable discharge chute cooperative with the discharge opening, and means for connecting and disconnecting the discharge chute to the drum, so that it may be turned by the drum, and stopped.
4. In a mixing machine, the combination of a mixing drum, a discharge chute therefor, and means for operatively connecting the drum with the discharge chute for actuation of the latter, said discharge chute being equipped with means for receiving the impact forces of concrete aggregates mixed in the drum, said last means, under the influence of said impact forces supplementing the connection of the chute with the drum, to move the chute.
5. In a mixing machine, the combination of a rotating mixing drum provided with a discharge opening, a rotative discharge chute cooperating with the discharge opening and means for connecting and disconnecting the discharge chute to the drum so that it may be turned by the drum, said chute having impact receiving members thereon arranged in the path of movement of the gravitating aggregates being mixed in the drum, whereby impact forces of said aggregates are transmitted to the chute to assist in turning the same.
6. In a mixing machine, the combination of a rotating mixing drum having a discharge opening, a discharge chute at said opening and movably mounted, said chute equipped with wing members arranged in the path of gravitational movement of aggregates in the drum so as to receive the impact forces of said aggregates and tend to move the chute, and automatic means for positively turning the chute to supplement the action of said impact forces.
7. In a mixing machine, the combination of a rotating mixing drum having a discharge opening, a discharge chute at said opening and movably mounted, said chute equipped with wing members arranged in the path of gravitational movement of aggregates in the drum so as to receive the impact forces of said aggregates and tend to turn the chute, and means for positively turning the chute to supplement the action of said impact forces, comprising mechanism for transmitting the rotative movement of the drum to the chute.
8. In a concrete mixing machine, in combination, a rotating drum having a discharge opening, a rotatable discharge chute at said opening and movable from an inwardly inclining position to an outwardly inclining position, and means to connect said chute with the drum to transmit movement of the drum to the chute for reversing its inclination as stated.
9. In a concrete mixing machine, in combination, a rotating drum having a discharge opening, a discharge chute rotatably mounted at said opening and movable from an inwardly inclining position to an outwardly inclining position, and means to connect said chute with the drum to transmit movement of the drum to the chute for reversing its inclination as stated, and an axis member connected with the chute to provide means for holding the chute in operative position and about which it may rotate.
10. In a concrete mixing machine, in combination, a rotating drum having a discharge opening, a discharge chute rotatably mounted at said opening and movable from an inwardly inclining position to an outwardly inclining position, and means to connect said chute with the drum to transmit movement of the drum to the chute for reversing its inclination as stated, means connected with the chute to provide an axis for holding the chute in operative position and about which it may rotate, and supporting rollers arranged beneath the chute and cooperative with said axis member to hold it in operative position.
11. In a concrete mixing machine, in combination, a rotating drum having a discharge opening, a discharge chute rotatably mounted at said opening and movable from an inwardly inclining position to an outwardly inclining position, and means to connect said chute with the drum to transmit movement of the drum to the chute for reversing its inclination as stated, means connected with the chute to provide an axis for holding the chute in operative position and about which it may rotate, supporting means cooperative with said axis member to hold it in operative position, a rockable bearing member on which said axis member is mounted and supporting means for said rockable bearing member.
12. In a mixing machine, in combination, a mixing drum, a rotatable discharge chute therefor having impact members, and means in the mixing drum for discharging concrete aggregates against the impact members of the chute for rotating the latter from one position to another, and automatic power means to supplement the action of the impact members for rotating the chute.
13. In a mixing machine, in combination,

- a mixing drum, a discharge chute therefor having impact members, and means in the mixing drum for discharging concrete aggregates against the impact members of the chute for moving the latter from one position to another and automatic means for locking the chute against movement under the action of the impact members.
14. In a mixing machine, in combination, a mixing drum, a discharge chute therefor having impact members, and means in the mixing drum for discharging concrete aggregates against the impact members of the chute for moving the latter from one position to another and means for locking the chute against movement under the action of the impact members, and common means for releasing the chute and for causing imparting thereto of mechanical force to supplement the action of the impact members, for moving the chute.
15. In a mixing machine, in combination, a mixing drum, a discharge device therefor, a batchmeter, control mechanism for connecting the discharge device with the drum to be actuated thereby, and means connecting the control mechanism with the batchmeter whereby a controlling relation is set up between the two by the batchmeter.
16. In a concrete mixing machine, in combination, a rotary mixing drum, a discharge device for the drum, means for interconnecting the drum and the discharge device whereby the latter may be operated from the drum, and a batchmeter operable to actuate the said interconnecting means.
17. In a concrete mixing machine, in combination, a rotating mixing drum, a rotating chute mounted to discharge the same, means for locking and releasing the chute and for connecting it with the drum to be actuated thereby, and batchmeter mechanism actuating the last above mentioned means.
18. In a mixing machine, in combination, a mixing drum, a discharge device therefor, means for holding the discharge device against movement, means for releasing the discharge device for movement and automatic mechanism for simultaneously actuating the releasing means and applying power to the discharge device to move the latter to operative position.
19. In a mixing machine, in combination, a mixing drum, a discharge device therefor, means for holding that discharge device against movement, means for releasing the discharge device for movement and automatic mechanism for simultaneously actuating the releasing means and interconnecting the discharge device and the drum whereby movement is imparted to the discharge device from the drum, together with means for stopping the movement of the discharge device in relation to the drum and restoring the action of the lock means for said discharge device.
20. In a concrete mixing machine, the combination of a mixing drum, a discharge chute therefor, movable to and from discharging position, a catch member on the discharge chute, an operating part on the drum to engage the catch member, and means to move the catch member into and out of positions for cooperation with said operating part on the drum.
21. In a concrete mixing machine, the combination of a mixing drum, a discharge chute therefor, movable to and from discharging position, a catch member on the discharge chute, an operating part on the drum to engage the catch member, and means to move the catch member into and out of positions for cooperation with said operating part on the drum, comprising a push lever, and a control member for actuating the push lever to connect the catch member with the drum, and means for disconnecting the catch member from the drum.
22. In a concrete mixing machine, the combination of a mixing drum, a discharge chute therefor, movable to and from discharging position, a catch member on the discharge chute, an operating part on the drum to engage the catch member, and means to move the catch member into and out of positions for cooperation with said operating part on the drum, comprising a push lever, and a control member for actuating the push lever to connect the catch member with the drum, and means for disconnecting the catch member from the drum, and a batchmeter connected with the control member aforesaid for control of actuation of the same substantially as described.
23. In combination, a mixing drum, a discharge device therefor, means to connect the drum and discharge device comprising a catch member on the latter, an operating part on the drum to be engaged by the catch member, a push lever for forcing the catch member into engagement with said operating part, a control slide for actuating the push lever and means to disengage the catch member from the operating part of the drum.
24. In combination, a mixing drum, a discharge device therefor, means to connect the drum and discharge device comprising a catch member on the latter, an operating part on the drum to be engaged by the catch member, a push lever for forcing the catch member into engagement with said operating part, a control slide for actuating the push lever and means to disengage the catch member from the operating part of the drum, including a trip lever, and an abutment in the path of movement of the trip lever.

25. In combination, a mixing drum, a discharge device therefor, means to connect the drum and discharge device comprising a catch member on the latter, an operating part on the drum to be engaged by the catch member, a push lever for forcing the catch member into engagement with said operating part, a control slide for actuating the push lever, and means to disengage the catch member from the operating part of the drum, including a trip lever, and an abutment in the path of movement of the trip lever, and means on the discharge device for restoring the control slide after it has actuated the push lever.

26. In combination, a mixing drum, a discharge device therefor, means to connect the drum and discharge device comprising a catch member on the latter, an operating part on the drum to be engaged by the catch member, a push lever for a control slide for actuating the push lever and means to disengage the catch member from the operating part of the drum, including a trip lever, an abutment in the path of movement of the trip lever, means on the discharge device for restoring the control slide after it has actuated the push lever, a batchmeter associated with the control slide, and means intermediate the batchmeter and control slide for initiating movement of the latter to operate the push lever.

27. In combination, a concrete mixing drum, a discharge device therefor, means to connect the drum with the discharge device for operating the latter, means for disconnecting the said parts from one another, and means for substantially simultaneously stopping the movement of the discharge device with the actuation and disconnecting means.

28. In combination, a rotative concrete mixing drum, a discharge device therefor, batchmeter control means for causing the application of power to the discharge device for setting it in an operative position, and means for simultaneously discontinuing the said application of power to the discharge device and stopping the same after it has reached the desired operative position, the power applying means comprising instrumentalities for directly connecting the drum with the discharge device to actuate the latter.

29. In combination, a rotary concrete mixing drum, a discharge chute therefor, control means for connecting the drum with the chute for moving the chute to an operative position, batchmeter means for controlling the said control means, manual means also controlling said control means, and interference means intermediate the batchmeter means and said manual means for preventing the manual means from acting to

control the control means under certain conditions.

30. In combination, a rotary concrete mixing drum, a discharge chute therefor, control means for connecting the drum with the chute for moving the chute to an operative position, batchmeter means for controlling the said control means, manual means also controlling said control means, and interference means intermediate the batchmeter means and said manual means for preventing the manual means from acting to control the control means during the period when the batchmeter is predetermined the lapse of the mixing period of agitating the aggregates in the drum.

31. In combination, a rotary concrete mixing drum, a discharge chute therefor, control means for connecting the drum with the chute for moving the chute to an operative position, batchmeter means for controlling the said control means, manual means also controlling said control means, and interference means intermediate the batchmeter means and said manual means for preventing the manual means from acting to control the control means during the period when the batchmeter is predetermined the lapse of the mixing period of agitating the aggregates in the drum, and said last means including parts which upon operation of the batchmeter at the end of the mixing period render the control means operative by the manual means aforesaid.

32. In combination, a rotary concrete mixing drum, a discharge device therefor, means for connecting the drum with the discharge device for actuation of the latter comprising a control mechanism, and manual means to set said control mechanism into action to connect the drum and discharge device and means to automatically disconnect the drum from the discharge device and stop the operation of the discharge device as influenced by the drum.

33. In concrete mixing apparatus, the combination, with a mixing container, of a shiftable chute cooperating to assist in the mixing operation and also in the discharge of aggregates from the container, and mechanical power means for shifting the chute, the chute being shaped and mounted for causing the aggregates to assist in the chute shifting operation.

34. In concrete mixing apparatus, the combination, with a rotary mixer having a discharge opening, of a discharge and mixing chute journaled to rotate at said opening, and an oscillatory support for the journal of the chute.

35. In concrete mixing apparatus, the combination, with a mixing container, of a chute therefor shiftable to different positions, power means for shifting the chute,

and both automatic and manual means for controlling the power means, both the automatic and the manual means being capable of complete control of the power means and one being adapted to be rendered inactive and thereupon leave the other in control of the power means.

36. In concrete mixing apparatus, the combination, with a mixing container, of a chute therefor shiftable to different positions, power means for shifting the chute, and both automatic and manual means for controlling the power means, both the automatic and the manual means being capable of complete control of the power means, the automatic means being adapted to be rendered inactive and thereupon leave the manual means in control of the power means.

37. In concrete mixing apparatus, the combination, with a mixing container, of a chute therefor mounted to shift to different positions, and a mounting for the chute affording floating movement thereof.

38. In concrete mixing apparatus, the combination, with a mixing container, of a chute therefor mounted to shift to different positions, a mounting for the chute affording floating movement thereof, and means bridging the area between the chute and container.

39. In concrete mixing apparatus, the combination, with a mixing container, of a chute therefor mounted to shift to different positions, a mounting for the chute affording floating movement thereof, and resilient means bridging the area between the chute and container.

40. In concrete mixing apparatus, the

combination, with a mixing container, of a chute therefor, a rotatable support for the chute, an oscillatory support for the rotatable support, and means bridging the area between the chute and container.

41. In concrete mixing apparatus, the combination, with a mixing container, of a chute therefor, a rotatable support for the chute, an oscillatory support for the rotatable support, and a splash plate surrounding the chute and bridging the area between the chute and container.

42. In concrete mixing apparatus, the combination, with a mixing container, of a shiftable chute therefor, power means adapted to be connected to shift the chute, automatic means for effecting such connection, and manual means for effecting such connection.

43. In concrete mixing apparatus, the combination, with a mixing container, of a shiftable chute therefor, power means adapted to be connected to shift the chute, automatic means for effecting such connection, manual means for effecting such connection, and means for preventing actuation of the manual means pending actuation by the automatic means.

44. In concrete mixing machines, the combination of a mixing drum, a discharge chute therefor mounted to move angularly substantially coaxially with the axis of rotation of the drum, and means for operatively connecting the drum to the chute for angularly moving the chute with the rotation of the drum.

In testimony whereof I affix my signature.
GEORGE E. WEBB.
